UNITED STATES PATENT OFFICE.

CHRISTOPHER F. BACKMYER, OF CHICAGO, ILLINOIS.

SNAP-FASTENER.

1,308,140.

Specification of Letters Patent.

Patented July 1, 1919.

Application filed May 11, 1918. Serial No. 233,839.

To all whom it may concern:

Be it known that I, CHRISTOPHER F. BACKMYER, a citizen of the United States, and a resident of the city of Chicago, in the county 5 of Cook and State of Illinois, have invented a certain new and useful Improvement in Snap-Fasteners; and I do hereby declare that the following description of my said invention, taken in connection with the accompanying sheet of drawing, forms a full, 10 clear, and exact specification, which will enable others skilled in the art to which it appertains to make and use the same.

My invention relates generally to improvements in snap fasteners; and it consists, essentially, in the novel and peculiar combination of parts and details of construction, as hereinafter first fully set forth and described and then pointed out in the 20 claims.

The object of my present invention is the production of fastening means of the snap-fastener type, whereby two articles may be readily and removably attached to each 25 other by a very simple manipulation, a fastener which shall be comparatively cheap in its manufacture, and which, is not liable to get out of order, especially so when applied to a washable article which when 30 passed through a clothes wringer is liable to be crushed or otherwise rendered ineffective. This fastener comprises but three parts two of which are made from sheet metal and can be produced in dies in large 35 quantities at a minimum cost, while the third member is a wire article which, likewise, can be readily produced in large quantities at a nominal cost.

In the drawings forming a part of this 40 specification, and disclosing the preferred embodiment of my invention, as well as several modifications thereof, Figure 1 is an inverted plan of what I shall hereinafter term the female member or element of this 45 fastener, the figure, as well as all the remaining figures of the drawings being drawn on a magnified scale. Fig. 2 is a sectional view on line 2—2 of Fig. 1. Fig. 3 is a like view, showing the parts of this fastener in the act 50 of being engaged. Fig. 4 is a plan view illustrating the parts in engaged condition.

Fig. 5 is an inverted plan view of a modified form of the female member of this fastening. Fig. 6 is a sectional view of the 55 same on line 6—6 of Fig. 5. Fig. 7 is an inverted plan of the latter fastener, showing

the parts in engagement. Fig. 8 is an inverted plan of still another modification of my device. Fig. 9 is a sectional view on line 9—9 of Fig. 8. Fig. 10 is a like view of the 60 fastener in assembled condition. Fig. 11 is a sectional fragmental view of a detail of this device.

Like parts are designated by the same characters and symbols of reference in all 65 the figures.

A, in all of the figures designates the female member; B, the male member; and C the catch employed in this device. This female member comprises, preferably, a circular disk which is, preferably, slightly concavo-convex, as indicated at 12, the marginal edge of which is rolled or formed into a bead 13, which bead, however, is open circumferentially, as shown in Figs. 2 and 3, and 70 other figures. In this disk A there is, preferably at one side of the center thereof, a circular opening 14, and terminating in this opening there is in the disk A a slot 15, narrower than the diameter of the opening 14, 80 the end of the slot 15 being, preferably semi-circular, as shown.

Located at the under side of the disk A, and crossing the slot 15 approximately medially of the disk, there is located a, preferably 85 wire, resilient member or spring C. This spring is, preferably, a single piece of wire bent approximately to U-shape, the members 16 of which are outwardly curved in opposing directions, as illustrated in Figs. 90 1 and 3, and other figures, the free ends of the spring as well as the cross member 17 thereof being tucked under the bead 13, and the cross member may be impinged, clenched upon by the marginal edge of the bead to 95 prevent displacement of said spring, or otherwise secured to said member A. The curvature of the members 16 of the spring 100 C is such that they meet in the center of the disk, as at 19, the object of which will later on appear.

In the disk A there are a series of small openings 18, near the margin thereof which afford means for securing the disk to any article or object to which it is to be attached, 105 by stitching, eyeleting, riveting, or other approved means.

The male member B, of this fastener is, preferably, a circular disk in every respect like the disk A, except that instead of the 110 openings 14, 15, therein, it has centrally a button 20, which is necked, as at 21, the

diameter of the button being slightly less than the diameter of the opening 14, and the external diameter of the neck 21 being slightly less than the width of the slot 15.

- 5 The operation of this fastener is essentially as follows: The elements A, B, being secured to the parts that are to be removably united, such as garments, curtains, gloves and others, the button of the male 10 part is inserted into the opening 14 of the female part and then laterally moved in the direction of the slot 15. This will cause the adjacent parts of the spring C to be depressed or moved away from the inner surface of the element A, to permit the button 20 to pass underneath the spring C. After 15 the button has passed the spring the latter will snap back to normal position and thereby hold the button in the slot. Pulling the 20 member B in the opposing direction will reverse the action of the parts and the parts readily separated.

I have heretofore stated that the elements A, B, are preferably of circular formation, 25 which is the best contour for production in large quantities in dies by means of punching presses; but it is evident that the shape or contour of these disks is practically immaterial as long as provisions are made for 30 retaining the spring C in position and permit of the necessary movement or deflection of the spring.

In Figs. 5, 6, and 7, I show a modified 35 form of construction of the device, the difference being in the contour and location of the spring C^a, which in this instance is axially alined with the opening 14 and slot 15, and medially, the members 16^a have oppositely directed projections or humps 22, 40 leaving between them a narrow space 23. The operation of this device is substantially the same as heretofore described except that the button 20 after passing the opening 14, when pushed laterally into the slot 15, the 45 spring members 16^a are forced apart to permit the neck of the button to pass these projections and then by resuming normal position, to hold the button behind said projections 22. A reverse movement of the button 50 produces releasing of the button, in an obvious manner.

In Figs. 8, 9, and 10, a slight modification of the device illustrated in Figs. 5, 6, and 7, is depicted. The elements A and B, are 55 still the same as first described; but the spring C^b, instead of having oppositely extending projections pointing toward each other, has central humps 24, directed toward the inner face of the element A. The button 20, after being passed through the opening 14, depresses the spring-members 16^b, which, after the button 20 has passed the humps 24, resume normal positions, so that the humps 24 hold the button in fastened 60 position, which, by a reverse movement of 65

the button causes the disengagement thereof. It will thus be noticed that as far as operation of the devices shown in Figs. 7 and 8 is concerned, it is the same, *i. e.*, the movement of the button causes a deflection or 70 bending of the spring members and the locking of the button by the humps or projections on the spring members engaging the button after it has passed into the slot 15 in the member A. 75

I have heretofore mentioned that the cross bar 17 of the spring C may be held in position by clenching or bending the bead 13 upon the bar 17. This feature is shown in Figs. 8 and 11, and is so obvious as not to 80 require any detailed description.

Having thus fully described this invention, I claim as new and desire to secure to myself by Letters Patent of the United States— 85

1. A snap fastener, including a female element, said female element having a slotted aperture and an enlarged opening in which said slotted aperture terminates, a male member, said male member having a button, 90 said button having a neck or constricted portion, and a spring member, said spring member comprising two curved members and a cross bar connecting said curved members at one of their ends, the curvature of said 95 spring members being such that medially of their length they are in close proximity of each other, said cross member being fixedly connected to the female element, the ends of the curved spring members being movably 100 held to the female member.

2. In a snap fastener, a female member, said female member being a plate, the marginal edges of said plate being formed into an open bead, there being in said plate a 105 slotted aperture, and an enlarged opening in which said slotted aperture terminates, and a spring, said spring being bent to approximately U-shape, the limbs of said spring being curved toward, and approaching each 110 other, said limbs being connected at one end, the latter end, and the terminals of said limbs being tucked into said open bead, the connected end of said limbs being fixedly held in position by said bead. 115

3. In a snap fastener, a female member, said female member being a circular disk, the marginal edge of said disk being formed into an open bead, there being in said disk a slotted aperture, and an enlarged opening 120 in which said slotted aperture terminates, a spring, said spring being bent to approximately U-shape, the limbs of said spring being curved toward, and nearly touching each other, said limbs being connected to a cross 125 bar, said cross bar, and the terminals of said limbs being tucked into the open bead, and a male member, said male member having a button, said button having a constriction or neck, the diameter of the button and that of 130

said neck being less than the diameter of the enlarged opening and the width of the slotted aperture, respectively, whereby by inserting said button into said enlarged opening said limbs are depressed to permit said neck to enter said slotted aperture, and after said button has passed said limbs to permit

said limbs to resume their normal position and to thus hold the male member in engaged position.

In testimony that I claim the foregoing as my invention, I have hereunto set my hand.

CHRISTOPHER F. BACKMYER.
